UNITED STATES PATENT OFFICE.

CLIFTON M. INGRAM, OF PORTER, OKLAHOMA, ASSIGNOR OF ONE-THIRD TO H. W. PRAMER, OF MUSKOGEE, OKLAHOMA, AND ONE-THIRD TO ROBERT DEDMON, OF PORTER, OKLAHOMA.

COMBINED SLEIGH AND BOAT.

Application filed April 5, 1928. Serial No. 267,637.

This invention relates to a combined sleigh and boat, and has for one of its objects to provide a novel, simple and inexpensive device of this character which shall 5 comprise a closed body, which shall be driven by air screws, which shall be capable of being readily steered while traveling over snow or ice or in the water, and which shall be heated by the exhaust gases of the propeller 10 motors.

With the foregoing and other objects in view, the nature of which will appear as the description proceeds, the invention consists 15 in the construction, combination and arrangement of parts hereinafter fully described and claimed, and illustrated in the accompanying drawings, wherein:

Figure 1 is a view in side elevation of the sleigh-boat,

Figure 2 is a view in front elevation of the sleigh-boat,

Figure 3 is a view in rear elevation of the sleigh-boat,

Figure 4 is a sectional view taken on a 25 vertical plane extending centrally and longitudinally through the sleigh-boat, and

Figure 5 is a sectional view taken on the vertical plane indicated by the line 5—5 of Figure 1.

The sleigh and boat comprises a closed body having tapered front and rear ends 1 and 2, respectively, and an intermediate portion 3 of substantially rectangular formation in cross section. The lower side 1^a 30 of the front end 1 inclines downwardly and rearwardly, the lateral sides 1^b incline outwardly and rearwardly, and the upper side 1^c inclines upwardly and rearwardly. The lower side 2^a of the rear end 2 curves down- 35 wardly and forwardly, the lateral sides 2^b incline outwardly and forwardly, and the upper side 2^c inclines upwardly and forwardly. The rear end of the side 1^c and the front end of the side 2^c are located above 40 the upper side 3^a of the intermediate portion 3, and the ends 3^b of the side 3^a are curved upwardly and connected to said ends of the sides 1^c and 2^c. The configuration of the body is such as to reduce to the minimum 45 the resistance offered to the movement thereof by air, water and snow.

The body is of laminated construction. Its outer layer 4 is made from steel, inner layer

5 from wood, and intermediate layer 6 from cork or other insulating material. The body 55 is provided in the lateral sides 1^b of its front end 1 with windows 7 and in the lateral sides 3^d of its intermediate portion 3 with windows 8 and doors 9, respectively. The frames of these parts have a water-tight 60 connection with the body. The body has a toilet room 10 which is provided by outwardly offsetting a portion of one of the sides 3^d, as shown at 11, and by erecting a frame 12 about the inner open side of said 65 offset portion. A door 13 is hung in the frame 12, and access to the toilet room 10 is had by way of steps 14. A toilet bowl 15 is suspended from the bottom side 16 of the offset portion 11, and said side constitutes 70 the seat for the bowl. Ventilators 17 and 18 are carried by the upper sides of the front end 1 and the intermediate portion 3, respectively.

The body is mounted upon rear runners 75 18 and front runners 19 which latter are pivoted, as shown at 20. The front runners 19, which are provided at their lower sides with ribs 19^a, are under the control of a steering mechanism which comprises a shaft 21 journaled in a housing 22 and provided with a wheel 23, a shaft 24 journaled in bearings 25 and 25^a, a drum 26 fixed to the shaft 24, a cable 27 wound about the drum and connected to the runners, and gears 28 connecting the shafts. The steering wheel 23 is arranged within convenient reach of the operator's seat 29.

A brake 30 which consists of side bars 31, a cross plate 32 and prongs 33 is pivotally 90 secured through the medium of the bars to the rear ends of the runners 18, as shown at 34. The brake 30 is adapted to be supported in an upwardly and rearwardly inclined inoperative position, and is adapted to 95 be lowered to and held in engagement with the snow or ice, by means which comprises bars 35 slidably mounted in stuffing boxes 36 and having, as shown at 37, pin and slot connections with the bars 31. The stuffing boxes 36 are carried by the lower wall 2^a of the rear end 2, and the bars 35 extend into the body and are provided with rack teeth. A sector pinion 38 journaled, as at 39, within the body meshes with the 100 bars 35 and is provided with an arm 40. A

lever 41 pivoted as at 42 within convenient reach of the operator's seat 29 is connected to the arm 40 by a link 43. Means 44 are provided for holding the lever in its adjusted position.

The sleigh and boat is provided at its front and rear ends with propellers or air screws 45 which are operated by internal combustion motors 46. Heating coils 47 are arranged within the body and connected to the exhaust pipes of the motors 46. Discharge nozzles 48 are provided for the heaters 47. The sleigh and boat is also provided with an antenna 49, and 15 with a rudder 50. The rudder 50 is under the control of a lever 51 pivoted within convenient reach of the operator's seat 29 and connected to the arm 52 of the rudder by a link 53. Any well known or 20 appropriate means, not shown, may be provided to permit the motors 46 to be controlled by the operator from his seat 29. A periscope 54 of any well known or appropriate construction is mounted on the body 25 for convenient use by the operator.

From the foregoing description, taken in connection with the accompanying drawings, it will be apparent that the sleigh and boat may be manufactured at a comparatively low cost, may be driven rapidly over snow or ice or in the water, and may be readily brought to a stop when traveling over snow or ice. The sleigh and boat affords ample protection against the elements, and 30 may be suspended from the fuselage of an air craft and used for exploring the polar regions.

It should be understood that the drawings are merely illustrative and do not pretend 40 to give exact proportions. Furthermore, the said drawings are illustrative of a preferred construction, it being my expectation that various changes and modifications may be made without departing from the spirit 45 and scope of my invention.

What is claimed is:—

1. A device of the character set forth, comprising a body, rear runners fixed to the body, front runners pivotally connected to the body, steering mechanism for the front 50 runners, a brake pivotally connected to the rear ends of the rear runners and provided with prongs, bars connected to the brake and extending into the body and provided with rack teeth, a pinion journaled within the 55 body and meshing with the rack teeth and provided with an arm, and means arranged within the body for operating the pinion to effect the raising or lowering of the brake.

2. A device of the character set forth, comprising a closed body, propelling and guiding means for the body, a portion of one side of the body being laterally offset, a frame within the body about the open side 65 of said offset portion and providing a space forming, with the space provided by the offset, a toilet room, a door hung in the frame, and a toilet bowl depending from the lower side of said offset portion and flush with the 70 upper surface of said side, said lower side of the offset portion forming a toilet seat extended towards the space enclosed by the frame.

3. A device of the character set forth, 75 comprising a closed body provided with tapered front and rear ends, windows arranged in the sides of the front end, windows and doors arranged in the sides of the body, motors carried by the front and rear ends, air screws fixed to the shafts of the motors, rear runners fixed to the body, front runners pivoted to the body, steering mechanism for the front runners, a brake secured to the rear runners, brake lowering and raising means, a rudder carried by the rear end of the body, and rudder operating means.

In testimony whereof I affix my signature.

CLIFTON M. INGRAM.
